IMPROVEMENTS IN WOOD LATHES.

WILLIAM H. WUSSOW, OF AURORA, ILLINOIS.

Letters Patent No. 60,317, dated December 4, 1866.

SPECIFICATION.

TO ALL WHOM IT MAY CONCERN:

Be it known that I, WILLIAM H. WUSSOW, of Aurora, in the county of Kane, and State of Illinois, have invented certain new and useful Improvements in Machines for Turning Axles, and other similar Irregular Forms; and I do hereby declare that the following is a full, clear, and exact description thereof, reference being had to the accompanying drawings of the same, which form part of this specification, and in which—

Figure 1 represents a top or birdseye view of a machine embracing my improvements.

Figure 2 represents an elevation of the front side of the same.

Figure 3 represents a vertical transverse section of the same at the dotted line xx of fig. 1.

Figure 4 represents a similar section taken at the line oo of fig. 1, showing the cutter frame turned upon its axis, so as to lift the cutters out of the way, in removing the finished article and replacing it with another piece of wood to be turned.

Figure 5 represents a similar section at the line xx of fig. 2.

In the accompanying drawings, A represents the frame, of rectangular form, and upon which the several parts of the mechanism are arranged and secured. The two longitudinal top pieces of this frame are metallic beams A' , having parallel ways $a a'$, to receive and guide a horizontal travelling carriage, and the standards which support the centres to which the pattern and the rough material are respectively secured. The ways $a a'$, which support and guide the cutter carriage, are formed on the inner upper sides of the beams A' , and the ways $a' a'$, for the centre standards, are outside of the ways $a a'$, so that the cutter carriage is located and travels between the centres of the pattern and of the material to be turned, while the pattern and the rough material are respectively located directly above the side beams of the frame. The standards B B' support tubular holders $b b'$, in which the fixed centres C C' are held and clamped by screws $c c'$. These standards are secured to the ways $a a'$ by clamp bolts $d d'$, passing through longitudinal openings $e e'$ in the metallic beams, so that they may be adjusted to suit the length of the pattern and the article to be turned. Two fixed standards D D' are secured to the beams A' , at the left end of the machine, and support mandrels E E', which carry and give motion to the centres F F', to which the pattern and the material to be turned are secured. These mandrels are made with sockets, and the centres are made with shanks, so as to fit into the sockets, and secured by screws. The fixed and revolving centres C and F have a common axis, but the centres which carry the pattern are higher than those which carry the material to be turned; the object of which will appear hereafter. The pattern G, represented in the drawings, is one-half the length of an axle, and shows therefore only a section of a full pattern; but it will be readily understood that the pattern, of whatever form, must be complete in the working machine. The carriage of the cutter frame consists of a horizontal open metallic frame H, fitted with grooves to receive the ways $a a'$, over which it is made to traverse back and forth, by a horizontal screw I, located centrally on the top of the frame, and having its bearings at each end thereof. The connection of the carriage with the feeding screw is made by means of an arm h (fig. 3) projecting from the right end of the carriage H, and having cut therein a female screw, into which the feeding screw fits and works. From each end of this carriage, a standard J rises, in whose upper ends the journals j are fitted which support the cutter frame K. This frame is composed of four bars, or may be cast in one piece, and is suspended by its journals j in a horizontal position, so that its supports will be nearer the rear end than the front end of the frame proper, and consequently cause its front end to preponderate, although its position when in operation will be always horizontal. Its length is greater than its width, and extends across the top of the frame, carrying at its front end the cutters, and at its rear end the guide which receives and transmits to the cutters the motions of the pattern. The cutter frame being thus located and arranged, brings the cutters directly over the material to be turned, and the guide directly beneath the pattern, and the weight of the cutter side of the frame preponderating, maintains the cutters in contact with the material and the guide in contact with the pattern. The cutters are mounted upon one end of a shaft having its bearings l in the front end of the frame K, nearly vertically in a line with the axis of the material to be turned, and they consist of two circular saws m , and arched or bowed blades, the former being secured by nuts and washers to two discs n , with a sufficient space between them to receive arched cutters o , also secured to the discs n . The circular cutters are of suitable diameter and of equal size, and are for roughing the material; and the cutters o occupy the space between them, being in this instance four in number, and composed of steel blades, bowed or arched, with their ends secured to the discs in any suitable manner that will admit of adjustment, and with their cutting edges projecting beyond the circumference of the circular cutters,

for the purpose of shaving and dressing the material. The discs are cast with a hub o' , and the circular cutters are secured to the outsides of the discs. From the opposite end of the cutter frame, an arm K' projects horizontally for supporting the guide L , directly beneath the pattern. The upper portion of the guide is convex, and is kept in contact with the surface of the revolving pattern by the preponderating weight of the front end of the cutter frame. It is secured to the arm by a thumb screw L' , which is free to turn, but is secured to the arm, so that the guide can be adjusted higher or lower, and thereby increase or diminish the size of the article to be turned, with one and the same pattern, by increasing or diminishing the amount of the vertical motion of the cutter; or the article may be turned the same size of the pattern. The guide is held firmly to the arm by two guide pins p , by one of which it is also champed by a screw q , for holding it securely when set. Coincident with the axis of the journals j , upon which the cutter frame is suspended, a shaft is secured in suitable bearings in said frame, upon which two pulleys, M M' , figs. 1 and 4, are secured; the smallest one M receives a band N from a long driving drum O , and the other M' receives a band M^2 , fig. 1, from a pulley M^3 on the cutter shaft, by which the proper motion is communicated to the cutters. As the axis of the pulleys M M' and the journals j of the cutter frame are vertically coincident with each other, and with the axis of the driving drum, the cutter frame is therefore allowed to vibrate upon its journals, in communicating the motions of the pattern to the cutter; or its front end may be raised up out of the way, as shown in fig. 4, without interrupting the motion of the cutters, the driving drum, or the carriage H . When the carriage is at the extreme of one of its motions, and the article being turned is finished, the front end of the cutter frame is raised in order to allow the finished article to be removed, and another piece of wood secured in its place, to be turned by the returning motion of the carriage; but as this end of the carriage is the heaviest, it therefore requires to be supported in its elevated position, which I do by means of a strut P , figs. 3 and 4, hinged at its lower end to the frame H , and notched at its upper end to receive a pin r , projecting from the side of the frame, as shown in fig. 3; and this convenience results from the manner of suspending the cutter frame, driving the cutters, and the arrangement of the pattern above the guide, and the material to be turned, beneath the cutters. The gearing for communicating the requisite motions to the pattern and rough material, is arranged at the left end of the machine, and consists of three cog wheels of equal size, and a small driving pinion at the back of the machine. The cog wheels q q' are mounted upon the outer ends of the mandrels which carry the centres F F' , and the intermediate cog wheel Q^2 is mounted upon an adjustable curved arm Q^3 , attached to and extending from one standard D to the other D' . As the gear wheels are liable to work loose, the ends of the curved arm are provided with slots to receive screw bolts, so that the intermediate wheel, Q^2 , can be properly adjusted when required. The pattern and the rough material, it will be seen, are centred so as to balance each other in their revolutions and thus prevent any unequal strain upon the gearing. The driving pinion, R , fig. 5, is mounted upon a shaft, R^1 , secured in a small frame, R^2 , pivoted to the standard, D' , so that by means of a screw passing through an arm of the frame, R^2 , and acting against a cross-bar of the standard, the pinion, R , may be raised or lowered in the arc of a circle to adjust it when required. On the outer end of the shaft, R^1 , there is a nest of cone pulleys, S , from one of which a band, S^1 , leads to one of a nest of cone pulleys, S^2 , directly below, on the end of a short shaft, S^3 , secured in suitable bearings to the side of the frame. On the inner end of this shaft there are one large and two small pulleys, from the former, T , a band, T^1 , leads to a small pulley, T^2 , fig. 5, on the left end of the shaft of the drum, O , from which the said shaft, S^3 , and its pulleys receive their motion. From the two small pulleys U U^1 , figs. 1 and 5, one of which, U^1 , is a clutch pulley, bands U^2 U^3 , lead to two larger pulleys, V V^1 , secured in suitable bearings at the front side of the machine. One of these bands, U^3 , is crossed for the purpose of reversing the motion of the cutter-carriage. To the outer end of the shaft, V^3 , a nest of cone pulleys, W , are secured from which a band, W , leads to a similar nest of pulleys, X , on the end of the central feed screw, I . From this arrangement of pulleys and bands, the gearing for operating the pattern, the material to be turned and the feed screw, receive their several and proper motions. To the outside of the front beam, two horizontal shifting rods, Z Z' , are secured by eye brackets s , in which they are free to be moved. One of these rods, Z' , is secured at its left end to the end of a bar, t , fig. 5, pivoted at the middle of its length to the under side of the end rail of the frame, and attached by its rear end, which is forked, to a clutch t' , on the shaft, S^3 , for connecting and disconnecting the clutch pulley, U^1 , on this shaft, and thus disengage the gearing for giving motion to the pattern and the rough material with the driving drum at pleasure. The other shifting rod, Z , is connected at its left end to a rod, u , pivoted to a bracket, u' , and having a forked end which embraces a clutch, v , on the shaft, V^3 , between the two clutch pulleys, V V^1 . This clutch and, Z , has an arm, w , near each end, made adjustable by screws, w' , so as to be nearer to or further from each other, to suit the length of the article being turned, in changing the motion of the carriage from right to left, and vice versa. To accomplish this a horizontal arm, x , is attached to and extends from the front side of the carriage, H , and is bent downwards at its front end so as to strike the stops, w , at the limit of the motion of the carriage each way, and thereby reverse its motion; the clutch pulleys being loose upon their shaft, of course cannot give motion to it, until either one is engaged with it, while the crossed-band from one of the pulleys reverses the motion of the feeding screw in a manner well known to machinists.

This machine is constructed to operate both ways, that is to say, by the motion of the cutters from right to left and from left to right. This feature is held to be a great advantage over other machines in obviating the necessity to wait for the slow return of the cutter-frame from one end of the machine to the other, after the article is finished, before operation can be again commenced. To accomplish this therefore, the arched or dressing cutters are provided with two circular roughing cutters or saws before described. One for roughing the material as the cutters move to the right, and the other for roughing a new piece secured to the centres, as the cutters move on their return motion to the left, and thus much time is gained and the effective operation of the machine is the same either way. For it will be seen, that when the article being turned is finished by the motion of the

carriage to the left, the cutter-frame is turned upon its axis so as to lift the cutters out of the way as shown in fig. 4, the right centre, C, is unclamped and the finished article removed; the axis of another piece of wood having been previously ascertained, is readily and properly secured to the centres and firmly clamped. The motions of the several parts being uninterrupted, the cutter-frame is again relieved from its support, P, and assumes a horizontal position ready to commence the operation from left to right, the pattern being always in its place, and the guide in contact therewith when the cutter-frame is down. It will be observed that to afford time to remove the finished article and replace it with another piece to be turned, the stops, w, are adjusted so as to allow the cutters to move some distance beyond the end of the finished article, before the motion of the feed screw is reversed, and as this motion is necessarily very slow it affords ample time to make the change before the cutters again approach the end of the rough material. The cutters and the guide being mounted at opposite ends of the pivoted frame, are presented, the former to the wood beneath by the greater weight of that end, and the latter to the pattern above. The driving centres are made to revolve very slowly, and the cutters with great rapidity, the carriage being caused to move slowly from one end of the machine to the other, and the cutters being free to move to or from the wood, and the guide being equally free to move to and from the pattern, it is plain that the inequalities of the pattern, as it rotates, will be communicated to the guide and transmitted to the cutters so as to cut the piece of wood an exact resemblance of the pattern. The band, N, which drives the cutters will traverse the drum with the motion of the carriage. The cutters revolve towards the pattern, and the rough material in the same direction, and the material being beneath the cutters the motions of the two therefore, meet in opposite directions, and as the cutters chip away the material, the shavings and chips are thrown out at the front of the machine. In order to do this effectually, and protect the travelling band, the drum, carriage, and other parts of the mechanism from being clogged with chips and dust, I attach a light case or fender, y, to the frame, K, so as to circulate the upper and rear portion of the cutters and extend downward a short distance in the rear thereof. Directly beneath this case a trough, y', is secured to the travelling carriage, H, with its rear end curved upward so as to meet and receive the end of the case and form a continuation thereof while its front end extends to the front of the frame. This chip case is thus made in two parts, both of which move with the carriage back and forth, while the upper one moves also vertically with the cutter frame and may be raised up with the cutters as shown in fig. 4. When the cutters however, are in the position to operate, the two parts, y and y', meet and form a continuous case to receive the cut chips and saw dust and discharge them at the front of the machine, and thereby prevent an accumulation of the cut material in piles beneath the machine or upon its working parts. The several gear-wheels and pulleys are of a diameter relatively such as to produce the proper degree of motion to each part of the operating mechanism.

Having thus described my improvements, what I claim, is—

1. So constructing and arranging the cutting and guiding frame, that its forward end, without the aid of extraneous devices, bears with a preponderating force down upon the work to be turned, while the rear end is caused to bear up against the pattern, substantially in the manner herein described.
2. The construction of the cutter with two circular saws, and intermediate finishing cutters, all arranged and operating substantially as described.
3. The arrangement of the device y y', with the longitudinally moving frame H, and the vertically swinging and longitudinally moving cutter-frame K, substantially as herein described.

In testimony whereof, I have hereunto signed my name.

WILLIAM H. WUSSOW.
